FIG. 5.

FIG. 6.

Inventor,
Julia Grothaus.
By her Attorneys
Glenwood & Glenscott

UNITED STATES PATENT OFFICE.

JULIA GROTHAUS, OF FORT SAM HOUSTON, TEXAS.

BLACKBOARD.

1,370,961.

Specification of Letters Patent.

Patented Mar. 8, 1921.

Application filed June 23, 1920. Serial No. 391,167.

To all whom it may concern:

Be it known that I, JULIA GROTHAUS, a citizen of the United States, residing at Fort Sam Houston, in the county of Bexar and State of Texas, have invented certain new and useful Improvements in Blackboards, of which the following is a specification.

The invention relates to display boards 10 and more particularly to display boards known as black-boards.

The object of the invention is to provide a display or black-board for use in schools or brokerage offices wherein the whole or 15 only a part of the writing may be displayed at one time although the board may be completely covered therewith.

A further object is to provide a board of 20 the above mentioned character wherein a portion of the writing thereon may be hidden from view by reason of the board's being raised, lowered, or rotated and the board so secured as to prevent unauthorized persons from arranging the same so that the 25 hidden portion may come into view.

A further object is to provide means to increase the usual limited black-board space in school rooms and at the same time to bring the top of the board, which is usually 30 not used, within reach of the writer from the floor level, after which it may be raised to a higher point.

With these and other objects in view, the invention resides in the several novel parts 35 and devices combined and arranged as hereinafter described and claimed.

In the accompanying drawings, in which like reference characters indicate corresponding parts and in which I have illustrated one embodiment of my invention:

Figure 1 is a front view of the preferred form of my device.

Fig. 2 is a sectional view of Fig. 1.

Fig. 3 is a longitudinal sectional view 45 of the preferred form of locking device for the boards.

Fig. 4 is a plan view of Fig. 3 with certain parts removed to show the essential features of the device more clearly.

Figs. 5 and 6 are sectional views of Fig. 50 3 on the lines $\alpha\alpha$ and $\beta\beta$ respectively.

In the application of my improvement I have designed an endless chain of slats A of suitable proportions and suitably joined, to 55 be mounted over rollers B, the rollers in turn being carried on shafts C, the said

shafts being supported by bearers D, guides E carried by the shafts C being provided in order to prevent the chain of slats from sagging between rollers. At suitable intervals 60 and at a desired distance from the ends of the slats A I have provided holes F for the double purpose of providing a catch for inserting the finger for rotating or raising the board and for the purpose of receiving the 65 latch of the locking device which is herein-after described.

The locking device consists of a suitable frame L, a flat spring steel piece M on which is mounted at its free end a lug N adapted 70 under certain conditions to enter the holes F for the purpose of securing the board against rotation, raising or lowering. In order to control the lug N and prevent its entering the holes F, or if it is desired to 75 lock the board to prevent its being forced out of locked engagement by unauthorized persons after the locking device has been actuated to prevent rotation or shifting of the board, I have provided a latch O, the 80 same being provided with a pivot P P, the upper pivot being extended at Q and formed into a stem of square cross section to receive a key, a small boss R being mounted over the stem for a finish.

For the purpose of better showing the device I have indicated the latch O in a sort of neutral position with respect to the flat spring M of the locking device; obviously 90 in this position the lug N would be in engagement with one of the holes F but would not be locked until the latch O was rotated clockwise until the face S' was under the spring in order to prevent the lug N being pushed out of locked relation with a hole F. 95 On the other hand, if the latch be rotated anti-clockwise from its present position until the face T' is disposed over the spring M and substantially at right angles thereto the spring will be depressed until the lug 100 N is withdrawn from the hole F, allowing the sash board or the endless chain board free movement. The slanting surfaces S and T of the latch are for the obvious purpose of gradually wedging the spring M to 105 either the locked or unlocked position, depending upon the direction the latch is rotated. The two flat surfaces S' and T' are the extreme positions of engagement or release of the spring. I have not so indicated 110 in the drawings, but I may in some instances install a crank arrangement for rotating the

endless chain board as a refinement. The seams U on the endless chain type of board will be faintly visible and will form a horizontal guide to assist the writer in making 5 neat, uniform writing.

In my device it is to be understood that I do not limit myself to any particular material, size, proportion, or details except in so far as such limitations are specified.

10 I claim:

1. In combination, a stationary frame, a plurality of thin strips joined in a manner to form an endless chain, two rollers mounted in said frame for carrying said endless 15 chain, a plurality of perforations near the ends of said strips, and a locking device secured to said stationary frame adapted to engage under certain conditions in one of the said perforations.

20 2. In combination, a stationary frame, a plurality of thin strips joined in a manner to form an endless chain, two rollers mounted in said frame for carrying said endless chain, a plurality of perforations near the 25 ends of the above mentioned strips, a metal strip pivotally mounted in said stationary

frame, a lug carried by said metal strip and adapted to engage in any one of said perforations when brought into register with said lug, and means for mechanically removing 30 or preventing the removal of the above mentioned lug.

3. In combination, a stationary frame, a plurality of thin strips joined in a manner to form an endless chain, two rollers mounted 35 in said frame for carrying said endless chain, a plurality of perforations near the ends of the above mentioned strips, a metal strip pivotally mounted in said stationary frame, a lug carried by said metal strip and 40 adapted to engage in any one of said perforations when brought into register with said lug, and a revoluble latch having a downwardly slanting surface and an undercut surface, said latch being further provided 45 with a square ended shaft fixedly secured thereto, the whole being mounted in a suitable frame and disposed in operative relation to the above mentioned metal strip.

In testimony whereof I affix my signature. 50

JULIA GROTHAUS.
